W. C. THOMA

SPARK PLUG

Filed Sept. 27, 1921

Inventor
William C. Thoma
by Cring & Hague Atty's.

UNITED STATES PATENT OFFICE.

WILLIAM CHRIS THOMA, OF LAURENS, IOWA.

SPARK PLUG.

Application filed September 27, 1921. Serial No. 503,637.

To all whom it may concern:

Be it known that I, WILLIAM CHRIS THOMA, a citizen of the United States, and resident of Laurens, in the county of Pocahontas and State of Iowa, have invented a certain new and useful Spark Plug, of which the following is a specification.

This invention relates to improvements in spark plugs in which the insulating member is formed of a series of transverse layers of mica or similar insulating material bound together by means of longitudinally extending rods. Insulating members constructed in this manner are very efficient as long as the edges of the layers are kept free from oil, but when the insulators are used in cylinders in which a considerable amount of oil is used, the spaces between the layers become saturated with oil and short circuiting results between the longitudinally extending terminal member and the casing of the spark plug in which the insulator is mounted. This is due to the fact that the space between the layers of mica become filled with conducting substances which enter the spaces between the discs or layers of material.

One of the objects of my invention is to overcome the above difficulty by providing means whereby the cylindrical face of the insulating member may be absolutely protected against oil from coming into engagement therewith.

A further object is to provide in a spark plug having an insulating member formed of a series of adjacent discs of insulating material, new and improved means for mounting the insulating member within the casing of the spark plug in such a manner that the circumferential edges of the discs will not be exposed to oil or similar substances.

A further object is to provide in a spark plug improved arrangement of spark terminals and the manner in mounting the same.

A still further object is to provide improved means for mounting the insulating member within the casing of a spark plug.

These and other objects will be apparent to those skilled in the art.

My invention consists in the construction, arrangement and combination of the various parts of the device whereby the objects contemplated are attained, as hereinafter more fully set forth, pointed out in my claims,

and illustrated in the accompanying drawings, in which:

Figure 1 is a side elevation of my improved spark plug.

Figure 2 is a longitudinal sectional view of the same taken on the line 2—2 of Figure 1.

My improved spark plug comprises a casing 10, the upper end of which is provided with a hexagonal nut 11, and the lower end of which is provided with a screw-threaded portion 12.

The casing 10 is provided with a centrally arranged cylindrical opening 13. The upper end of the opening 13 is provided with a screw threaded portion 14, the lower end of the casing is provided with a cylindrical opening 15 of a slightly less diameter than the opening 13 so that a slight inclined inwardly extending shoulder 16 is provided. The lower end of the opening 15 is provided with an inwardly extending flange 17, the inner edges of which form an opening 18. The portion 12 is of standard diameter and provided with standard threads.

The insulating member 19 of my improved spark plug is preferably formed of a series of discs of mica and laid adjacent to each other and bound together by means of centrally located conductor rods 20.

These rods 20 are spaced a slight distance apart and have their upper ends screw threaded and extending through a plate 21, and each provided with a nut 22.

The plate 21 is formed U-shaped so that the upper portion of said member 21 lies above the nuts 22 and is provided with a terminal screw 23. The said screw is provided with the usual terminal nut 24 so arranged that connection may be made between a suitable conductor wire and the plate 21.

The lower ends of the rods 20 extend downwardly through the lower end of the insulating member 19, and are provided with collars 25 which rest adjacent to the lower end of said member 19, thereby providing means whereby the discs of said member may be rigidly clamped between the collars 25, and the plate 21 forming the member 19 into a rigid insulator.

The central portion 26 of the insulator 19 is formed cylindrical and of a diameter

slightly less than the diameter of the opening 13 and designed to rest in said opening when in its normal position.

The upper end of the member 19 is formed 5 slightly conical, the lower end of the conical member being of a less diameter than the member 26 to form a shoulder 27.

The shoulder 27 and the adjacent portion 10 of the member 19 is provided with a conical sleeve 28 having an outwardly extending flange 29, the flange 29 being designed to rest on the shoulder 27, and the portion 28 being designed to snugly fit the lower end of the conical portion.

15 A screw threaded bushing 30 is provided and designed to coact with the screw threaded portion 14. The said bushing is provided with a hexagonal nut 31 and with a conical opening 32 designed to fit the outer surface 20 of the member 28, while the inner end of the bushing 30 rests against the flange 29. The opening in the bushing, however, is loose enough so as to permit the said bushing to rotate freely on the sleeve 28. This forms 25 means whereby the insulator may be secured in the casing as will hereinafter be made clear.

Adjacent to the lower end of the cylindrical portion 26, I have provided a smaller cylindrical portion 33, and adjacent to the lower end of the cylindrical portion 33, I have provided a downwardly extending conical portion 34, the upper end of the conical portion 34 being of less diameter than the portion 33 to form an annular shoulder 35. The diameter of the portion 33 is slightly 30 less than the diameter of the opening 15, while the diameter of the lower end of the conical portion 34 is of a diameter substantially equal to the diameter of the opening 18.

40 Mounted upon the portion 33, I have provided a shell 36 of thin sheet metal having a number of annular and outwardly extending beads 37, and at its lower end an annular and inwardly extending flange 38. The inner edge of the flange 38 is designed to rest against and overlap the lower end of the insulating member 19.

50 The space between the shell 36 and the conical portion 34 is filled with asbestos or some other insulating, heat-resisting material 39. In assembling the shell 36 the member 39 is placed adjacent to the portion 34, then the shell 36 is placed over the member 39 and the said casing squeezed longitudinally onto the member 33. This will cause the member 39 to be packed and squeezed to a very condensed condition so as to positively 55 engage the ends of the discs forming the portion 34, and thereby form an oil tight joint to prevent the oil from seeping between the discs.

60 After the shell 36 has been squeezed into 65 position, the upper edge of said shell is

spun into the cylindrical portion 33, as shown at 40, so as to prevent the said shell from moving out of position due to the expansion of the material within.

By this arrangement, it will be seen that 70 I have provided an insulating member comprising the member 19, the shell 36 and the packing 39 in a unitary form which may be removed or placed in the casing 10 when so desired. The beads 37 are of such diameter 75 that they will be squeezed into position as the member 19 is moved downwardly into the opening 15, and as they engage the inclined shoulder 16, thereby forming a tight joint between the beads and the wall of the 80 opening 15 to prevent oil from entering the space between the portions 26 and 33 and the walls of the opening 13.

To further assist in preventing the oil 85 from working upwardly between the insulating member and the casing 10, I have provided a packing washer 41 which is similar to those used in spark plugs.

The packing 41 is placed between the flange 38 and the flange 17. When the bushing 30 is screwed into the casing 10 the said flanges will be moved toward each other and engage the packing 41, thereby forming a 90 tight joint.

95 By making the bushing 30 loosely mounted on the sleeve 28, the said bushing may be screwed into position and the insulator clamped without rotating the said insulator and destroying the contact between the packing 41 and the adjacent flanges, the beads 37 100 and the adjacent wall.

105 By forming the sleeve 28 so that it tightly fits the member 19, the portion 28 of the said sleeve will be made to carry a portion of the force applied by the 110 bushing 30, and to distribute the said force to a large number of discs of the member 19 rather than applying all of the pressure to the shoulder 27 as has been done heretofore. When all the pressure is applied to the shoulder 27, it causes the disc adjacent to the bushing 30 to be sprung downwardly and a fracture or opening will result between the lower end of the 115 conical portion and the upper end of the cylindrical portion 26. By providing the conical sleeve 28 the pressure is applied substantially uniform to all of the discs and no fracture will result.

120 The lower ends of the members 20 are curved slightly inwardly toward each other to form a spark gap. A ground member 42 is provided, the lower end of which is spaced a slight distance from the lower ends of the members 20. This provides a double means whereby the spark may be made to jump between either of the members 20 and the member 42. The lower ends of the members 20 and the member 42 are of considerably greater length than is used in the or- 125 130

dinary spark plug as I find it gives better results.

By this arrangement, it will be seen that I have provided a spark plug, the insulating member of which may be formed of mica or similar material and so arranged that oil or similar substances will not enter the space between the discs. The insulating member may be easily and quickly removed from the casing when so desired, for cleaning and renewing. It will also be seen that I have provided improved means whereby the said insulator may be effectively and efficiently secured in the casing without destroying or breaking down the discs of the insulating member.

I claim as my invention.

1. A spark plug comprising a casing having a cylindrical opening at its central portion, the inner end of said opening being provided with an inwardly extending flange, an insulator formed of a series of adjacent and transversely arranged disks, said insulator being provided with an enlarged cylindrical portion designed to fit the upper end of the opening of said casing having an upwardly and outwardly extending end and a downwardly extending cylindrical portion, the lower end of which is formed conical, a packing member for the conical portion of said downwardly extending end, means secured to the downwardly extending cylindrical portion for securing said packing in position, means for securing said insulator member within said casing, a conductor member for said insulator, and a ground member for said casing placed in operative relation with each other.

2. A spark plug comprising a casing having a cylindrical opening in its central portion and a smaller cylindrical opening adjacent to one end, the inner end of said smaller opening being provided with an inwardly extending flange, the outer end of said larger cylindrical opening being screw threaded, an insulator formed of a series of adjacent and transversely arranged disks, said insulator being provided with a cylindrical portion designed to fit the larger opening of said casing, the lower end of said insulator being provided with a smaller cylindrical portion and a smaller conical portion, a packing member for covering the last said conical portion and means for securing said packing member thereto, a conductor extended longitudinally through said insulator, a terminal screwed to the upper end of said conductor, a ground conductor in operative relation with the first said conductor, a screw threaded bushing designed to coact with the screw threaded portion of said casing and to secure the insulator in position.

3. A spark plug comprising a casing having a cylindrical opening at its central por-

tion and a smaller cylindrical opening adjacent to one end, the inner end of said smaller opening being provided with an inwardly extending flange, the outer end of said larger cylindrical opening being screw threaded, 70 an insulator formed of a series of adjacent and transversely arranged discs, said insulator being provided with a cylindrical portion designed to fit the larger opening of said casing, and with a conical upwardly 75 extending end, a sleeve for said upwardly extending conical portion, a bushing for said sleeve, a conductor extending longitudinally through said insulator, a terminal screw for the upper end of said conductor, the lower 80 end of said insulator being provided with a smaller cylindrical portion, and a smaller conical portion, a packing member for the last said conical portion, and means for securing said packing member thereto, a packing ring between the lower end of said insulator member and the annular flange of said casing, a ground conductor in operative relation with the first said conductor.

4. A spark plug comprising a casing, an 90 insulator member mounted therein, a double conductor arranged longitudinally through the center of said insulator having the lower ends of its members bent slightly toward each other, a collar on each of said members 95 spaced apart and designed to rest against the lower end of said insulator, the spacing of said collars being less than the spacing between the downwardly projecting end, a terminal at the upper end of said insulator member being connected to both of said conductors, means for securing said insulator in said casing, and a ground conductor 100 in operative relation with the first said conductors.

5. A spark plug, a casing having a cylindrical opening at its central portion and a smaller cylindrical opening adjacent to one end, the inner end of said smaller opening being provided with an inwardly extending flange, an insulator formed of a series of adjacent and transversely arranged disks, said insulator being provided with a cylindrical portion designed to fit the larger opening of said casing and a smaller upwardly extending end, the lower end of said insulator being provided with a smaller cylindrical portion and a smaller conical portion, a packing member for the last said conical portion, means for securing said packing member thereto, a packing ring between the lower end of said insulator member and the annular flange of said casing, a conductor extended longitudinally through said insulator, a ground conductor in operative relation with the inwardly extending end of the first said conductor, means for detachably securing the insulator member within said casing.

Des Moines, Iowa, September 2, 1921.
WILLIAM CHRIS THOMA.
